AUTOMATIC SIGNALING SYSTEM FOR
RAILWAYS

Georges Caille, Vaujours, France, assignor, by
mesne assignments, to The Union Switch &
Signal Company, Swissvale, Pa., a corporation
of Pennsylvania

Application May 3, 1935, Serial No. 19,734
In France November 14, 1934

22 Claims. (Cl. 246—41)

This invention relates to a safety arrangement applicable to railway signaling systems utilizing "track circuits". It is understood that the track circuit is a portion of the track defined at its ends by insulated joints and includes at one end a source of supply, at the other end a relay, the battery and the relay being connected to the rails.

It has already been proposed to provide against possible false operation of the relay due for instance to mechanical sticking or to insufficient shunting produced by the train during its travel, by combining the relay with another relay in such a manner that the risk of false operation of the combination is reduced to the product of the risks of false operation of each of the safety devices considered singly.

The invention has for its object an improvement in these two relay systems with a view, while always ensuring safety by means of the second relay, of permitting the non-operation of the first relay to be disclosed for the purpose of its subsequent rectification. According to the invention, in fact, the non-operation of one of the relays effects through the action of the second relay the setting of the signal to "stop", this indication instead of being automatically reversed after the passing of the train as in normal operation being maintained until the first relay again becomes operative.

The accompanying Figures 1 to 4 inclusive of the drawings illustrate diagrammatically by way of example four different relay systems.

The system of Figure 1 comprises in the known manner two track relays A and B, connected in parallel instead of a single relay, the indication that the track is occupied—that is to say, the illumination of the green lamp V and the red lamp R—being effected by the deenergization of one of the relays or of both relays.

According to the invention, a third relay C is employed which provides against the false operation of one of the relays A or B by maintaining the indication "track occupied" so long as the two track relays are not operated in agreement with each other, that is to say, until the normal operation of the two relays is reestablished.

For this purpose the relay C is slow releasing, and its energizing (pick-up) circuit including the back contacts 1 and 2 of the two relays A and B is as follows: from terminal +, contact 1, contact 2, coil of relay C to terminal —. A stick circuit for the relay C is furthermore provided including the front contacts 3 and 4 of the relays A and B and the stick contact viz. from terminal

+, contacts 3, 4, and 5, coil of relay C to terminal —. Each of the relays C, B, and A further comprises the usual contacts 6—7, 8—9, 10—11 effecting in the energized condition the illumination of the white lamps B¹ and in the deenergized condition the illumination of the lamps V and R.

The operation is as follows:—

The entrance of a train in the track circuit K causes the simultaneous deenergization of the relays A and B, which results in effecting through a circuit from terminal +, contact 11 and the return circuit, the illumination of the red and green lamps of the signal. At the same time the armatures of the relays A, B move from the position in which the front contacts 3, 4 are closed to a position in which the back contacts 1, 2 are closed and during this movement the relay C is not released owing to its being slow acting while when the back contacts 1, 2 are closed the energizing circuit of the relay is maintained through these contacts so long as the relays A and B are deenergized.

Assume on the other hand that one of the two relays A or B remains stuck in its attracted position after the entrance of a train into the section K. If it is the relay A, the illumination circuit of the signal is effected through the circuit: terminal +, contacts 10, 9 and the return circuit.

At the same time the relay C is deenergized by the opening of the front contact 4, the back contact 1 not being closed, so that contact 5 of relay C is thus opened.

It will be readily seen that the same action will occur if it is the relay B which has failed to operate, the relay A having operated normally.

When the train has left the section K, the two relays A and B will both be restored to their energized conditions, but the relay C will remain deenergized, its energizing current being cut off at the open contact 5. The signal thus continues to exhibit the red and green "stop" lamps.

Assume that a second train enters the section K. If the relays A and B this time operate normally the signal indication will be properly given at the signal by the closing of back contact 11; at the same time the relay C will be energized through the circuit —, terminal +, contacts 1 and 2, coil C and the return circuit and the relay C will automatically remain energized through the contact 5. Normal conditions will thus be re-established and the signal lamps will be extinguished when the track section K is free. If one of the two relays A or B still does not operate normally, the signal will continue to exhibit the

stop indication until another train re-establishes the normal operation of the relays, or until the failure to operate having been indicated the relay A has been repaired.

5 Figure 2 shows another method of control of the track relay A by an auxiliary relay B and a mechanical pedal P. The relay A has the usual contacts 10-11 which, in normal operation, close the circuit of the lamps V and R through the 10 contact 11 upon the entrance of a train into the section K.

The relay A comprises as before a contact 1 controlling in this case the energization of the relay B. The latter is provided with two energizing circuits, the first circuit including the contact 1 and the contact 13 of the pedal P which is opened when the pedal is depressed by the passage of a train; the second circuit is a stick circuit including the relay contact 2 and the contact 13 of the pedal P. The relay B comprises two contacts 6 and 7 controlling the signal lamps in the same way as the contacts 6 and 7 of the relay C of Figure 1.

The operation is as follows:

25 In normal operation, the entrance of a train into the track circuit K effects the deenergization of the track relay A, which at its back contact 11 causes the closure of the illuminating circuit of the lamps R and V. At the same time, the 30 energizing circuit of the relay B is closed at the back contact 1 but the pedal P being depressed by the passing of the train the contact 13 of this circuit is opened.

The relay B being deenergized establishes at its 35 back contact 7 the illumination of the lamps R and V. After the train has passed beyond the pedal P, and before it has passed out of the track circuit K, the energizing circuit of relay B is completed from terminal +, back contact 1, contact 40 13, and effects the energization of this relay and consequently the closure of the stick circuit of relay B at the contact 2. The front contact 6 is thus closed, and as soon as the train has left the track section K, the front contact 10 is also closed 45 and the lamps B1 are illuminated while the lamps V and R are extinguished.

If on the contrary, when the section K is occupied, the relay A remains stuck up, the relay B will release as soon as the pedal P has been 50 operated by the train, and its contact 7 will cause the red and green lamps of the signal to be illuminated. When the train has released the pedal, the relay B cannot be re-energized since the contact 1 is open, and the contact 7 remains 55 closed so that the red and green lamps remain illuminated. If a second train comes into the section K and if the relay A operates normally, the back contact 11 will be closed and will illuminate the "stop" lamps of the signal and as 60 soon as the pedal P is released by the second train, the relay B will be re-energized. Normal conditions will thus be established. If on the other hand the relay A still remains stuck up, the relay B will remain deenergized and the "stop" 65 signal lamps will remain illuminated until normal operation of the relays has been re-established.

Figures 3 and 4 represent two methods of controlling the relay A in which the relay B and the pedal P are associated with a slow release relay C. 70 In addition to the ordinary contacts 10 and 11 controlling the illumination, either of the "stop" lamps R and V, or of the "line clear" lamps B1, three contacts 1, 15, 16 are provided on the relay A. The front contact 1 closed when the relay is 75 energized, closes the energizing circuit of the

relay B in which are included not only the contact 13 operated by the pedal P, but also the contact 14 operated by the relay C. The front contact 15 closed when the relay A is energized, controls an energizing circuit for the relay B in parallel with the first circuit above mentioned, and the back contact 16 controls the energization of the relay C. 5

The relay B comprises in addition to the ordinary contacts 6 and 7 controlling the illumination of the "stop" or "line clear" signal lamps, two contacts 17 and 18. The front contact 17 is connected in the stick circuit of the relay B which also includes the front contact 15. 10

The contact 18 controlling the energization of the relay C, is included in a stick circuit in which the contact 19 is also included. 15

The operation is as follows:—

In normal operation when the train enters the section K, the relay A releases and effects the illumination of the "stop" signal lamps R, V at 20 its back contact 11. The relay B on the other hand is deenergized both by the opening of the front contact 15 as a result of the deenergization of the relay A and by the action of the pedal P as the train passes. The relay A in releasing 25 energizes the relay C on the other hand at the back contact 16. After the track circuit has become unoccupied, the contact 13 having previously become reclosed, the relay B is reenergized through the following circuit: front contact 1, 30 contact 14 (still maintained closed due to the slow release of relay C) contact 13, coil of relay B, to terminal —.

This re-energization of the relay B effects the closing of the front contact 17 and consequently 35 maintains the relay B energized after the deenergization of the relay C.

If, on the contrary, the relay A fails to operate, that is to say, remains stuck up when the train enters the section K, the relay B will be deenergized by the passage of the train over the pedal, as a result of the opening of the contact 13. The closure of the back contact 9 when the relay B is deenergized will then effect the illumination of the "stop" signal lamps R and V. The relay C 45 will not operate.

When the train has left the track section K, the relay B will remain deenergized since neither of its energizing circuits have been re-established. The signal will continue to exhibit the "stop" lamps 50 V and R, so long as a train has not re-established the normal operation of the relay A.

The system of Figure 4 differs from the preceding systems in that the number of the contacts of the main relay is reduced which gives an advantage from the point of view of convenience in installation. 55

In the system of Figure 4, the contact 1 of the Figure 3 operated by the relay A and included in the energizing circuit of the relay B has been 60 replaced by a contact 20 operated by the relay B itself and connected in the stick circuit of the relay C.

The operation of the system of Fig. 4 is as follows: With the apparatus in the condition illustrated, when a train enters section K, relay A will release and will open the stick circuit for relay B at front contact 15. Relay B will now release, opening the circuit for signal B1 at front contact 8 and closing the circuit for signal V, R at back contact 9. If for any reason relay A should fail to release promptly, the stick circuit for relay B will be opened at the pedal contact 13. 65

As soon as relay A releases, the pickup circuit for relay C becomes closed at back contact 16 so 70

that relay C picks up and closes a holding circuit for itself which circuit includes back contact 20 of relay B and front contact 19 of relay C. Relay C in picking up closes front contact 14, thus preparing the pickup circuit for relay B.

5 As soon as the train leaves the section, relay A will pick up and will close the pickup circuit for relay B at front contact 15 whereupon relay B will pickup. The closing of front contact 17 completes the stick circuit for relay B, and the opening of back contact 20 interrupts the stick circuit for relay C which, therefore, releases. The apparatus is now restored to the condition illustrated in the drawings.

10 15 Should relay A fail to release when a train enters section K, the subsequent release of relay B due to the opening of pedal contact 13 will interrupt the stick circuit at contact 17. Accordingly, since contact 14 will not be closed because of the failure of relay A to release and to pick up relay C, relay B will remain deenergized until such time as a subsequent train movement succeeds in releasing relay A.

20 25 It should be pointed out that if relay C is so designed that its release time is sufficiently long to enable relay B to pick up following the exit of a train from the section, then the holding circuit for relay C including back contact 20 of relay B and front contact 19 of relay C can be eliminated 30 without interfering in any way with the proper operation of the system.

35 30 Although I have herein shown and described only a few forms of apparatus embodying my invention, it is understood that various changes and modifications may be made therein within the scope of the appended claims without departing from the spirit and scope of my invention.

Having thus described my invention, what I claim is:

40 1. In combination with a section of railway track, a pair of track relays both receiving energy from the rails of said section, an auxiliary relay, a pickup circuit for said auxiliary relay effective when both of said track relays are released, a holding circuit for said auxiliary relay effective when both of said track relays are energized, and traffic governing apparatus controlled by both said track relays and said auxiliary relay.

45 2. In combination with a section of railway track, a pair of track relays both receiving energy from the rails of said section, an auxiliary relay, a pickup circuit for said auxiliary relay including a back contact of each of said track relays, a holding circuit for said auxiliary relay including a front contact of each of said track relays as well as a front contact of said auxiliary relay, and traffic governing apparatus controlled by both said track relays and said auxiliary relay.

50 3. In combination with a section of railway track, a track relay receiving energy from the rails of said section, a normally energized auxiliary relay, means exclusive of said track relay and effective when a train enters said section for de-energizing said auxiliary relay, a pickup circuit for said auxiliary relay controlled by said track relay, a holding circuit for said auxiliary relay including a front contact of the auxiliary relay, and traffic governing apparatus controlled by both said track relay and said auxiliary relay.

55 4. In combination with a section of railway track, a track relay receiving energy from the rails of said section, a normally energized auxiliary relay, means including a train operated contact for deenergizing said auxiliary relay, a pickup circuit for said auxiliary relay including a con-

tact of said track relay and said train operated contact, a holding circuit for said auxiliary relay including a front contact of the auxiliary relay and said train operated contact, and traffic governing apparatus controlled by both said track relay and said auxiliary relay.

5 10 15 5 In combination with a section of railway track, a track relay receiving energy from the rails of said section, an auxiliary relay, a pickup circuit for said auxiliary relay including a normally closed train operated contact, a holding circuit for said auxiliary relay including a front contact of the auxiliary relay and said train operated contact, and traffic governing apparatus controlled jointly by said track relay and said auxiliary relay.

15 20 25 6 In combination with a section of railway track, a track relay receiving energy from the rails of said section, a normally energized auxiliary relay, a pickup circuit for said auxiliary relay including a contact of said track relay which is closed when the track relay is deenergized, a holding circuit for said auxiliary relay including a front contact of the auxiliary relay, and traffic governing apparatus controlled by both said track relay and said auxiliary relay.

25 30 35 7 In combination with a section of railway track, a track relay receiving energy from the rails of said section, a normally energized auxiliary relay, means effective when a train enters said section for deenergizing said auxiliary relay, a pickup circuit for said auxiliary relay including a back contact of said track relay, a holding circuit for said auxiliary relay including a front contact of the auxiliary relay, and traffic governing apparatus controlled by both said track relay and said auxiliary relay.

35 40 45 8 In combination with a section of railway track, a track relay receiving energy from the rails of said section, a normally energized auxiliary relay, means including a train operated contact for deenergizing said auxiliary relay, a pickup circuit for said auxiliary relay including a back contact of said track relay and said train operated contact, a holding circuit for said auxiliary relay including a front contact of the auxiliary relay and said train operated contact, and traffic governing apparatus controlled by both said track relay and said auxiliary relay.

45 50 55 9 In combination with a section of railway track, a track relay receiving energy from the rails of said section, a normally energized auxiliary relay, a pickup circuit for said auxiliary relay including a front contact of said track relay, a holding circuit for said auxiliary relay including a front contact of said track relay and a front contact of said auxiliary relay, and traffic governing apparatus controlled by both said track relay and said auxiliary relay.

60 65 70 10 In combination with a section of railway track, a track relay receiving energy from the rails of said section, a normally energized auxiliary relay, means effective when a train enters said section for deenergizing said auxiliary relay, a pickup circuit for said auxiliary relay controlled by said means and by a front contact of said track relay, a holding circuit for said auxiliary relay controlled by a front contact of said track relay and including a front contact of said auxiliary relay, and traffic governing apparatus controlled by both said track relay and said auxiliary relay.

70 75 11 In combination with a section of railway track, a track relay receiving energy from the rails of said section, a normally energized auxil-

22. In combination with a section of railway track, a track relay receiving energy from the rails of said section, an auxiliary relay, a pickup circuit for said auxiliary relay including a back contact of said track relay, a holding circuit for said auxiliary relay including a front contact of

the auxiliary relay, means effective when a train enters said section for interrupting said holding circuit, and traffic governing apparatus controlled by both said track relay and said auxiliary relay.

GEORGES CAILLE.
